UNITED STATES PATENT OFFICE

JEREMY LAKE AND ANDREW W. ELLIOTT, OF NORTH EASTON, MASS.

IMPROVEMENT IN SPADES.

Specification forming part of Letters Patent No. 126,465, dated May 7, 1872.

Specification describing a new and Improved Spade, invented by JEREMY LAKE and ANDREW W. ELLIOTT, of North Easton, in the county of Bristol and State of Massachusetts.

The drawing represents a front view of our improved spade.

This invention relates to a new spade with forked or **U**-shaped blade, which will enter the ground with greater ease than the plain, full blades now in use.

A, in the drawing, represents the blade of the spade. A notch is cut into it at the middle, and extending from the lower edge about half way up the length of the blade, more or less. The blade has thus the shape of an inverted letter **U**. Its lower cutting-edges *a* may be slightly rounded, as shown, or straight.

A spade thus made will, with less difficulty, cut through the ground, and will crumble the soil with less effort than the full-bladed spades, though it has sufficient surface not to break the clods while it supports the same. In its attachment to the handle **B** this spade may not vary from those now in use.

Having thus described our invention, we claim as new and desire to secure by Letters Patent—

As a new article of manufacture, the bifurcated spade herein described.

JEREMY LAKE.

ANDREW W. ELLIOTT.
